United States Patent Office

Des. 212,070
Patented Aug. 27, 1968

212,070

EDIBLE SNACK PRODUCT

Bohdan O. Hreschak, Hawthorne, N.J., assignor to National Biscuit Company, a corporation of New Jersey

Filed Aug. 15, 1967, Ser. No. 8,280

Term of patent 14 years

(Cl. D1—2)

I claim:

The ornamental design for an edible snack product, substantially as shown.
